US00D360374S

United States Patent [19]

Tice et al.

[11] Patent Number: Des. 360,374

[45] Date of Patent: ** Jul. 18, 1995

[54] HOUSING FOR A SMOKE DETECTOR

[75] Inventors: Lee D. Tice, Bartlett; Eric W. Anderson, St. Charles, both of Ill.

[73] Assignee: Pittway Corporation

[**] Term: 14 Years

[21] Appl. No.: 23,087

[22] Filed: May 18, 1994

[57] CLAIM

The ornamental design for a housing for a smoke detector, as shown and described.

DESCRIPTION

FIG. 1 is a perspective view of a housing for a smoke detector showing our new design;

FIG. 2 is a side elevational view thereof, with the opposite side being a mirror image; and,

FIG. 3 is a top plan view thereof with the bottom being flat and unornamented;

Fig. 1

Fig. 2
